DESIGN.

—o—
W. L. JACOBS.

CARPET.

No. 17,487.

Patented July 26, 1887.

UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 17,487, dated July 26, 1887.

Application filed June 15, 1887. Serial No. 241,435. Term of patent 3½ years.

To all whom it may concern:

Be it known that I, WINTHROP L. JACOBS, of East Orange, New Jersey, have invented a new and original Design for Carpets, of which 5 the following is a specification, reference being had to the accompanying photograph, which forms a part of the same.

The invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

15 The main feature of my design is the group A, having a comparatively long slender mass, presenting the appearance of a succession of

substantially circular flower forms closely massed along a wavy line and touching or partially overlapping one another, and having a row of dependent lichen-like forms projecting from the flower forms. 20

The whole design consists in the irregular repetition of groups substantially like the group A, all as clearly shown in the photograph. 25

What I claim as new, and desire to secure by Letters Patent, is—

The design for carpets, consisting of the design substantially as shown.

W. L. JACOBS.
